UNITED STATES PATENT OFFICE.

JOHN ALEXANDER McNABB, OF COLLINGWOOD, ONTARIO, CANADA, ASSIGNOR OF ONE-
THIRD TO GEORGE TINEGATE, OF COLLINGWOOD, ONTARIO, CANADA.

DETACHABLE MEANS FOR LIFE-BOATS.

1,246,968.

Specification of Letters Patent. Patented Nov. 20, 1917.

Application filed June 8, 1917. Serial No. 173,628.

To all whom it may concern:

Be it known that I, JOHN ALEXANDER McNABB, of the city of Collingwood, county of Simcoe, Province of Ontario, Canada, a subject of the King of Great Britain, have invented certain new and useful Improvements in Detachable Means for Life-Boats, of which the following is a specification.

My invention relates to improvements in detachable means for life boats, and relates more particularly to that type of detachable means wherein the coupling means coupling the boat at each end to the davits are simultaneously released by a lever mechanism which is operated amidships, and the principal object of my invention is to provide emergency coupling means so that in case it be impossible to uncouple the life boat from the tackle carried by the davits, by the operation of the lever mechanism hereinabove described or its equivalent, either or both ends of the life boat may be readily uncoupled by hand. Another object of my invention is to provide a very simple lock for the actuating lever.

The preferred construction of my invention will be hereinafter particularly set forth, and what I claim as new will be pointed out in the claims forming part of this specification.

Figure 1 is a vertical central longitudinal section through a life boat, showing my detachable means in side elevation, certain parts being cut away to illustrate internal construction. Fig. 2 is an end elevation of one of the standards carrying the coupling means. Fig. 3 is an elevation of the actuating lever and the locking means therefor, and Fig. 4 is a side elevation of the coupling means carried by the upper ends of the standard illustrated in Fig. 2, showing the emergency uncoupling means knocked down.

In the drawings, like characters of reference refer to the same parts.

I have found from actual practice that during stormy and cold weather on the Great Lakes, ice is apt to form on the tackle and coupling means, whereby said tackle is coupled to the life boats, and the consequence is that it has been found impossible to readily uncouple the life boat from the davits under such circumstances, and therefore some emergency uncoupling means

must be provided so that both ends of the life boat may be readily uncoupled under the circumstances just noted, and by the occupants of the boat.

The improvements herein described and hereinafter pointed out in the claims, I have made in the invention patented to myself and the late Gilbert Emery on July 25, 1916 under Number 1,192,543.

A is the boat and mounted at each end thereof is a suitable standard preferably formed of two upright members B, spaced apart. The upper portions of these upright members are coupled together by the tie-bolts C, and the lower ends of the said members are preferably coupled together by the cross pieces D. A suitable construction for coupling the standards B to the boat comprises bolts E held in the keel F. Pivoted on each of the tie-bolts C is a hook G. These hooks are preferably positioned midway the standards B, and they are held in this spaced relationship, in respect of the members B, by any suitable means such as the thimbles H mounted on said tie-bolts. Each hook is coupled by a link-arm I to a bell-crank lever J, which is pivoted on a tie-member K held in the standards B. The said bell-crank levers are held in suitable spaced relationship in respect of the members B, by any suitable means such as the thimbles L. Each bell-crank lever is coupled by a connecting rod M with the actuating lever N which is positioned amidships. This actuating lever N is pivoted on the tie-member O mounted in the members P of the standard Q, and is suitably held in spaced relationship in respect of said members, as will be understood. As hereinafter particularly described, the actuating lever N is unlocked, and by moving it in the direction indicated by arrow 95 in Fig. 1, the hooks G are disengaged from the coupling members 2 carried by the block and tackle 3, (only partly shown) which are coupled to the davits, not shwon. When the hooks G and their supporting parts are not coated with ice, they can readily be moved to disengage the life boat, as described. When they are coated with ice, they cannot be moved readily, and to overcome this disadvantage, I have provided each hook G with what I may term a keeper, which performs the function of an emergency uncoupling means. These keepers 4

are preferably U-shaped as shown in Fig. 2, and through the sides 5 thereof pass a tie bolt 6 which passes through the upper ends of the members B of the end standards. 5 These tie-bolts are held from withdrawal by any suitable means such as nuts 7. The normal position of the keepers 4 is illustrated clearly in Fig. 1; they overlap the ends 8 of the hooks G. To hold these 10 keepers in this position, they are pinned to the members B by any suitable means such as the split pins 9 passed through holes 10 formed in the sides 5; and through holes 11 (shown by dotted lines in Figs. 4 and 2) 15 formed in the members B. Should it be impossible, for any reason whatsoever, to move the hooks G to uncouple the boat, the pins 9 can be readily knocked out of position and thus permit the keepers 4 to be knocked 20 down into the position illustrated in Fig. 4, thus allowing for the ready disengagement of the coupling members 2 from the hooks G.

The split-pins 9 or their equivalents, are coupled to the boat by any suitable means 25 such as the chain 12. 13 are suitable braces for the end standards which may be used if desired.

Pivoted to the lever N by the pin 14 is a latch 15, the nose 16 of which normally rests 30 in the slot 17, (shown by dotted lines in Fig. 3) formed in the thwart 18. The side members 19 of the latch 15 are spaced apart, and between them passes the lever N. 20 is a lug or bar carried by the side members 19 of 35 the latch 15, and against this lug or bar, the spring 21 rests. This spring is carried by the lever N, and its function is to maintain the nose 16 in the slot 17. Any suitable means may be employed to keep the latch 40 15 coupled to the thwart 18 when desired.

It is only necessary to move the lever N in one direction to uncouple the hooks G, and since the described means for locking the said lever to the thwart is very simple,

I have reduced to a minimum any possibility 45 of the actuating lever N jamming.

If desired, I may secure shields 22 to the bottom of the boat, and over the major portion of the length of the connecting rods M.

Any suitable turn-buckle 23 or equivalent 50 means may be used on the rods M to provide for adjustment and wear.

The upper portion of the lever N rests normally in a slot a formed in the side of the 55 thwart 18.

I do not confine myself to the construction herein shown and described for putting my invention into practice since the scope of protection desired is pointed out in the 60 following claims.

Claims.

1. The combination with a boat; standards supported one at each end thereof; a coupling hook pivoted to each of the said standards, and having its free end projecting thereabove; and means whereby said coupling hooks may, under suitable conditions, be moved to uncouple the boat from the coupling members supported by the davits; of a keeper pivoted to each of said 65 standards; and means whereby said keepers are locked to maintain them normally in the path of releasing movement of said coupling members.

2. The combination with a boat; standards supported one at each end thereof, and each composed of two upright members spaced apart; a hook pivoted between said upright members and having its free end normally extending above the top of its associated standard; a keeper substantially U-shaped in form, pivoted to said uprights at the upper end of each of said standards, said keepers normally designed to project above said standards and over the free ends of 80 said hooks, and means whereby said keepers may be locked against movement.

JOHN ALEXANDER McNABB.
